UNITED STATES PATENT OFFICE.

THOMAS MIDGLEY, OF WORTHINGTON, OHIO, ASSIGNOR TO MORGAN & WRIGHT, OF DETROIT, MICHIGAN, A CORPORATION OF MICHIGAN.

WIRE-TAPING MACHINE.

1,179,545.

Specification of Letters Patent. Patented Apr. 18, 1916.

Application filed March 18, 1914. Serial No. 825,485.

To all whom it may concern:

Be it known that I, THOMAS MIDGLEY, a citizen of the United States, residing in Worthington, county of Franklin, and State of Ohio, have invented certain new and useful Improvements in Wire-Taping Machines, of which the following is a full, clear, and exact description.

This invention relates to machines for applying a spiral wrapping of tape to wire hoops for use in the manufacture of tire shoes or casings. In constructing these hoops it is customary to coil a continuous wire in a plurality of convolutions, and couple the ends by twisting them together, the hoop so formed being then trained over two revoluble pulleys which are thereupon moved apart to tauten the hoop, and during passage of the hoop over the pulleys in the nature of a belt, a layer of tape is helically wound thereupon to anchor the convolutions together. A disadvantage found in this method of manufacture is that the two pulleys tend to tension the convolutions of the hoop unequally, thus impairing the durability and life of the hoop.

To obviate the above disadvantage I provide a machine in which an endless series of radially movable concentric pulleys are employed to expand the hoop to nearly the contour of a circle, in contradistinction to the elongated hoop contour assumed when a pair of pulleys are employed, whereby the various convolutions of the hoop are more equally tensioned than usual.

In the accompanying drawings, I have illustrated one form of the machine which may be used in practising my invention, in which drawings:

Figure 1 is a plan view of the machine; Fig. 2 is a longitudinal sectional view of the machine; Fig. 3 is a longitudinal sectional view taken in a plan view at a right angle to that shown in Fig. 2; Fig. 4 is an enlarged detail plan view showing the shuttle; Fig. 5 is a cross sectional view on the line 5—5, Fig. 4; Fig. 6 is a cross sectional view on the line 6—6, Fig. 5; Fig. 7 is a cross sectional view on the line 7—7, Fig. 4.

Referring to the drawings, 10 designates the frame of the machine. Centrally disposed within the frame is an upright shaft 11 which is driven from a drive shaft 12 by means of meshing worm gears 13 and 14. The drive shaft is actuated by a motor 15 and rotation of the drive shaft is controlled

by a foot pedal 16 and shift link mechanism 17 which operate a friction clutch 18 on the drive shaft.

Fixed to the upright shaft is a bevel gear 19 which meshes with and drives bevel gears 20 carried by radially disposed stub shafts 21 which are supported in bearings 22 depending from radially extended arms 23 which bridge and are secured to the top of the frame as shown at 24. Mounted to slide longitudinally on each shaft is a bearing 25 which is equipped with a guide flange 26 that works in a guide slot 27 formed in the related arm 23, the bracket carrying a pulley 28 which is driven from the related shaft 21 by meshing bevel gears 29 and 30. In the present embodiment an endless or circular series of five pulleys 28 are shown, the same being spaced equally apart and being adapted to support the wire hoop 31 from the inside, as shown in Fig. 1, thus shaping the hoop nearly in the contour of a circle. During rotation of the shaft 11, the shafts 21 rotate the pulleys 28 to feed the hoop in a circular path through a shuttle which will presently be described.

To move the pulleys radially outward to tauten the convolutions of the hoop, the bearings 25 are pivotally connected to respective shift links 32 that converge downward to and are pivotally connected to a common collar 33 that is mounted for vertical movement on the upright shaft 11. A lever 34 is pivoted at the outer end on the frame, as shown at 35, and is pivoted at the inner end to the collar, as shown at 36. The lever is preferably connected to the piston 37 of a compressed air motor 38 carried by the frame. An air pipe 39 is connected to the motor and is controlled by a two-way valve 40 which establishes communication between the motor and an air supply when swung open in one direction, and vents the motor to the atmosphere when swung open in the opposite direction. When the valve is opened to admit air to the motor the piston actuates the lever 34 to raise the collar 33 whereby the arms 32 are extended laterally and shift the bearings 25 and their pulleys 28 outwardly, this outward pressure of the endless series of pulleys against the hoop from the inside expanding and yieldably holding the hoop expanded, whereby the convolutions thereof are equally tensioned. When the valve is opened to vent the motor to the atmosphere, a spring 40

on the upright shaft 11 urges the collar downward with a resultant withdrawal of the pulleys inwardly to release the hoop.

A rotary shuttle 41 is mounted in a bearing 42 carried on a web 43 that connects a pair of the radial arms 23, the shuttle being driven from a drive shaft 44 by means of meshing gears 45 and 46. Both the shuttle and its gear 45 are slotted radially to their 10 axis as shown at 47 to receive the hoop 31. The shuttle carries an integral transverse arm 48 to which is secured a spindle 49 which receives a spool 50 of tape 51, the spool being removably secured on the spindle by a cap 52. The spindle extends at an angle of approximately 45 degrees from the axis of the shuttle, and during rotation of the shuttle carries the tape spool circumferentially around the hoop, whereby the tape 15 is wound helically on the hoop as the latter progresses in a path through the shuttle in the direction of the arrow head in Fig. 4.

To move the shuttle radially in unison with the pulleys the bearing 42 of the shuttle is dove-tailed to slide on a guide rib 52 carried by the web 43. An arm 53 is fixed to the guide flange 26 of the adjacent pulley 28, the arm having a longitudinal slot 54 which slidably receives a pin 55 carried by 20 the shuttle bearing. During radial movement of the shuttle the arm 53 will simultaneously carry the shuttle radially so that the shuttle is positioned at all times to receive the hoop. The drive shaft 44 is feathered to slide in its bearing 56 to accommodate this radial movement of the shuttle, the shaft being driven by a chain drive 57 from a stub shaft 58 which is in turn driven from the main drive shaft 12 by a gear drive 59.

40 In operation the wire hoop is trained over the pulleys 28 and through the shuttle 41. The machine is then set in operation by opening the air valve 33 whereupon the pulleys and shuttle are simultaneously moved 45 radially outward and uniformly tauten the wire convolutions of the hoop. The end of the tape is now pressed onto the hoop by the operator and the pedal 16 depressed, whereupon the pulleys are rotated and carry 50 the hoop in a circular path through the shuttle, which is simultaneously rotated to apply the tape helically on the hoop. After a round of tape has been applied to the 55 hoop, the tape is then cut, and the air is then released to withdraw the pulleys inwardly and permit removal of the taped hoop.

Having thus described my invention, what 60 I claim and desire to have protected by Letters Patent is:

1. In a machine of the class described, a

circular series of pulleys for supporting a hoop from the inside, and pneumatically operated means for simultaneously moving the 65 pulleys radially outward and yieldably holding them in this outward position to tauten the hoop.

2. In a machine of the class described, a circular series of radially movable pulleys 70 for supporting a hoop from the inside, a shuttle movable radially in unison with the pulleys for applying tape to the hoop, and means for rotating the pulleys on their axes to advance the hoop in a path through the 75 shuttle.

3. In a machine of the class described, an endless series of pulleys for supporting a hoop from the inside, a drive shaft concentric with said pulleys, and radially disposed 80 shafts driven from the drive shaft and rotating said pulleys.

4. In a machine of the class described, a frame, an endless series of pulleys for supporting a hoop from the inside mounted on 85 the frame for radial sliding movement, a drive shaft concentric with said pulleys, radially disposed shafts driven from the drive shaft for rotating said pulleys, and means for moving the pulleys in unison longitudinally of said driven shafts to tauten the hoop. 90

5. In a machine of the class described, an endless series of pulleys for supporting a hoop from the inside, means for spreading the pulleys apart radially to tauten the hoop, 95 a shuttle for applying tape to the hoop, and an arm carried by one of the pulleys and operatively connected with the shuttle for moving the shuttle radially in unison with said pulley. 100

6. In a machine of the class described, a revolute shuttle, an endless series of revolute pulleys for supporting a hoop from the inside and moving the hoop is nearly a circular path through the shuttle, and a tape 105 supply spool carried by the shuttle to one side of and at an angle to the path of the hoop for applying a wrapping of tape helically to the hoop.

7. In a machine of the class described, a 110 frame, an endless series of radially movable pulleys on the frame for supporting a hoop from the inside, a shuttle mounted for radial sliding movement on the frame, means for moving said pulleys and said shuttle radially in unison, and means for simultaneously rotating said pulleys and said shuttle 115 on their axes.

Signed at Detroit, county of Wayne, State of Michigan, this 13th day of March, 1914. 120

THOMAS MIDGLEY.
